RAILWAY SPIKE.

1,416,819.

Specification of Letters Patent. Patented May 23, 1922.

Application filed February 14, 1922. Serial No. 536,466.

To all whom it may concern:

Be it known that we, HUBERT E. HARRIS and JAMES H. DOWNEY, citizens of the United States, and residents, respectively, 5 of Jonesboro, in the county of Clayton and State of Georgia, and of Gainesville, in the county of Hall and State of Georgia, have invented certain new and useful Improvements in Railway Spikes, of which the following is a specification.

The invention relates to railway spikes, and has as an object the provision of a spike which will be prevented from lifting out of the tie by coaction with the under- 15 side of the rail, or a tie plate underlying the rail.

A further object of the invention is the provision of a spike which will offer greater resistance to withdrawal than spikes now in 20 use.

An illustrative embodiment of the invention is shown in the accompanying drawing, in which—

Figure 1 is a vertical transverse section 25 through a rail and a portion of a tie showing the spike in elevation for use with a tie plate;

Fig. 2 is a similar view showing a spike in use without a tie plate, the spike being 30 slightly modified in form;

Fig. 3 is a side elevation of a portion of a rail showing a spike in elevation and a portion of a tie in section and,

Fig. 4 is a view showing a rail in section 35 illustrating the position in which the spike is held at starting, drawn upon a reduced scale.

The form of the invention shown in Fig. 1 is adapted for use with a tie plate 10 shown 40 as having ribs 11 on the lower side, the outer edges of the ribs being located so as to fall vertically under the edges of the base 12 of the rail 13. The ribs 11 are shown as cutting into the material of the tie 14 upon 45 which the rail is carried. To permit of placing of the spike 15 the plate is provided with apertures 16 at suitable points, the apertures being slightly wider than the stock of the spike.

50 The spike embodying the invention has a usual head 17 provided with the usual overhanging lip 18. Below the lip on the inside of the spike is a straight vertical portion 19 which is adapted to come opposite the base 55 of the rail and the thickness of the tie plate

11. Opposite the straight portion 19 is a second straight portion 20, so that the spike for a short distance below the head is parallel sided and vertical when in place.

Below the straight portion referred to 60 the spike is bodily offset in the direction of the lip 18. The width of the spike throughout to the point 21, where the reduction in width to form the point is begun, is substantially uniform. The offset below the 65 parallel sided portion above referred to provides at 22 an inclined portion which underlies the adjacent edge of the rib 11 and will come in contact therewith if the spike attempts to lift in the tie. Opposite this 70 inclined portion the offset referred to provides a cam surface 23 which serves, while the spike is being driven, to force the spike toward the rail by contact with the material of the tie. At the point 24 the offset upon 75 the back of the spike ends and the surface of the spike from this point downward again becomes vertical and is continuous to the point 25 of the spike. The front of the spike also has a straight portion 26 opposite the 80 straight portion at the back from a point 26 to the point 21 already referred to. The curved portion 27 by which the point of the spike is formed acts as a cam surface during the first portion of the driving of the spike. 85

The spike is driven by starting it in the position shown in Fig. 4, slanted away from the rail, and with the tangent 28 to the curve 27 at the point of the spike substantially vertical. As the spike enters the wood the 90 cam surface 27 will force the point of the spike to the right, seen in Fig. 4, thereby bringing the spike toward the vertical. When the surface 23 comes in contact with the opening 16 in the tie plate and later 95 with the material of the tie 14 the spike will be forced bodily toward the rail, and at the completion of the driving the inclined portion 22 of the spike will underlie the tie plate and effectually prevent any tendency 100 to lift out of the tie.

The form of the invention shown in Fig. 2 is exactly similar in action to that shown in Fig. 1, the only difference being that the vertical portion 19 is shortened to compensate for the absence of the thickness of the tie plate. The inclined portion 22 underlies the rail exactly as the portion 22 underlies the tie plate and the cam surfaces 23' and 27' acting during driving exactly as do 110

the corresponding cam surfaces in the form shown in Fig. 1.

The point of the spike, as shown in Fig. 3, is preferably provided with a plurality 5 of notches 29 to lessen the surface which penetrates the wood in the starting of the spike so that the same may be caused to stand ready for driving with less application of force.

10 Tests made upon the resistance of the spike to withdrawal establish that a substantially greater force is required to pull the spike from the tie than is the case with the straight spikes in common use at the 15 present. This is true when the spike is driven into a block in the absence of a rail or tie plate. When in use the weight upon the rail, in addition to its action directly upon the surface 22, acts to hold down the 20 fibres of the tie which fibres must yield upwardly to allow the tie to be lifted vertically. Therefore the resistance to lifting is very much greater than that of the usual 25 straight spike. The tendency of a rail to tip over under thrust of wheel flanges, especially on curves provides a very great pulling force upon the spikes, so much so that upon curves where traffic is heavy it is necessary to send track men frequently to 30 drive the spikes down.

The form of spike illustrated by the present invention is such that the weight of slower moving traffic upon the rails positively returns to place any spike which may 35 have been started, so that no difficulty is found with lifting spikes. The spike provided by the present invention can be readily withdrawn by placing a claw bar across the head of the rail, giving the spike an outward and upward pull to start it, after 40 which it may be withdrawn in the usual manner.

Minor changes may be made in the physical embodiment of the invention without 45 departing from its spirit.

Having thus described our invention what we claim as new and desire to secure by Letters Patent is:

1. A railway spike comprising a head, an 50 overlapping lip, a perpendicular surface beneath said lip adapted to come opposite objects to be held, a surface below said perpendicular surface inclined downward and away from the plane thereof and adapted

to underlie held objects, a perpendicular surface on the back of said spike opposite said first named perpendicular surface, a cam surface below said perpendicular surface adapted to throw said inclined surface under held objects by contact with the material in- 55 to which the spike is driven.

2. A railway spike comprising a head having an overhanging lip, a surface below said lip inclined downward and in the direction of overhang of said lip and adapted to 60 underlie an object to be held by said lip, a cam surface opposite said inclined surface adapted to throw said inclined surface under the object to be held by contact with the material into which the spike is driven.

3. A railway spike comprising, in combination, a head having an overhanging lip, a surface below said lip inclined downward and in the direction of overhang of said lip 65 and adapted to underlie an object to be held by said lip, a cam surface opposite said inclined surface and upon the back of the spike adapted to throw said inclined surface under an object to be held, a perpendicular portion below said inclined surface and cam 70 surface, and a point sloped away from the front of the spike so as to turn the spike in the tie with the head pressed toward the object to be held.

4. A railway spike comprising, in combination, a head having an overhanging lip, parallel vertical surfaces upon the front and back of the spike adjacent the head, a body offset in said spike toward the front side 90 thereof below said vertical surfaces providing a downwardly and forwardly inclined surface upon the front of the spike to underlie a held object, and a cam surface on the back of the spike to throw said inclined surface toward the object when the spike is driven, parallel vertical surfaces upon the front and back of the spike below said last named offset, the vertical surface on the back of the spike extending to the point thereof, 95 a curved cam surface extending from the second named vertical surface on the front of the spike to the point thereof, said last named cam surface adapted to throw the spike to a vertical position after being started into a tie in a slanting position.
